UNITED STATES PATENT OFFICE.

JOHN E. WEBSTER, OF PITTSBURGH, PENNSYLVANIA, ASSIGNOR TO WESTINGHOUSE ELECTRIC AND MANUFACTURING COMPANY, A CORPORATION OF PENNSYLVANIA.

LOCOMOTIVE-BEARING.

1,080,032.

Specification of Letters Patent.

Patented Dec. 2, 1913.

Application filed June 20, 1910. Serial No. 567,908.

To all whom it may concern:

Be it known that I, JOHN E. WEBSTER, a citizen of the United States, and a resident of Pittsburgh, in the county of Allegheny and State of Pennsylvania, have invented 5 a new and useful Improvement in Locomotive-Bearings, of which the following is a specification.

My invention relates to electric locomotives and other vehicles which are propelled by electric motors and it has special reference to such vehicles as are adapted to haul heavy loads at very high speeds.

The object of my invention is to provide 15 an improved journal box or bearing structure for electric locomotives and other railway vehicles which shall be simple and durable and be specially adapted for use with locomotives having relatively low centers 20 of gravity.

In electric locomotives having propelling motors of large size suspended between the driving wheels, with their armatures concentric with the wheel axles or with their 25 armature axes in substantially the same plane as the axle axes, the center of gravity of the locomotive is relatively low, which is generally regarded as disadvantageous on account of the fact that the various movements of the body and frame of the locomotive, in operation, are apt to produce 30 heavy strains in the rails and wheel flanges instead of being absorbed by the carrying springs, as is the case if the center of gravity 35 is high. It is evident that it is not the absolute height of the center of gravity, but the height of the center of gravity above the point, or points, at which the side thrust is transmitted from the frame to the wheel 40 axle that is important. The points in question usually lie in a horizontal plane through the center of the wheel axle, since the guide ways which hold the journal boxes in the side frames of the locomotive are 45 tapered slightly from this plane outwardly in both directions.

According to my present invention, I taper the guide ways from a point near the bottom of the journal boxes and thereby materially lower the point where the end thrusts, due to swinging of the locomotive frame, are applied to the journal boxes.

Figure 1, of the accompanying drawings, 50 is a partially sectional elevation of an electric locomotive embodying my invention,

and Figs. 2, 3 and 4 are, respectively, a front and side elevation and a plan view of a journal box constructed in accordance with my invention. Fig. 5 is a view corresponding to Fig. 3 and showing one-half 60 of the journal box on a larger scale, in order to more clearly illustrate my invention.

Referring to the drawings, the locomotive here shown comprises a cab or body 1, cross ties 2, side frames 3 and 4, wheel axles 5, 65 an electric driving motor 6, and journal boxes 7 and 8. The side frames are supported and held in position by the journal boxes which rest on the ends of the axle.

Each of the journal boxes 7 and 8 comprises a body portion 9, having slots or channels 10 to receive the usual pedestal legs 11 of the side frames that are protected by channel shaped spacing shoes 12. The shoes 12 are fitted closely to the pedestal 70 legs 11, and the grooves or channels 10 in the body 9 are of such form and dimensions as to fit the shoes closely at their lower ends but have diverging side walls that permit of considerable lateral movement of the 75 pedestals and shoes in the upper portions of the grooves or channels. The lateral movements of the side frame with reference to the journal boxes are rotative in character because the said frames are held in contact 80 with the journal boxes at their lower edges, the said movements being absorbed by the 85 usual side springs (not shown) of the locomotive.

By the means which I have devised, it is 90 possible to obtain an increase of about a foot in the distance between the center of gravity and the point in the side frames where the end thrust is transmitted to the boxes.

Structural modifications may, of course, 95 be effected within the spirit and scope of my invention.

I claim as my invention:

1. In a railway vehicle, the combination with side frames having U shaped pedestals, 100 and wheel axles, of a journal box adjustably supported in the pedestal and having lateral projections for holding the journal box in position, said projections being in engagement with the pedestal legs at their lower 105 ends and gradually diverging therefrom.

2. In a railway vehicle, the combination with side frames having a plurality of pedestals to receive journal boxes and wheel 110 axles, of journal boxes adjustably supported

- in the pedestals of the side frames and having guide projections forming taper guide ways which fit the pedestal legs closely at their narrowest point, near the bottoms of the boxes.
3. In a railway vehicle, the combination with a body having notched side frames and cross ties and wheel axles, of journal boxes mounted on the axles and adjustably supported in the notches of the side frames, said journal boxes being provided with lateral projections beveled to form tapered guide ways which are narrowest at the bottoms of the boxes.
4. A journal box for electrical vehicles having lateral projections which are beveled to form tapered guide ways which are narrowest near the bottom of the box.
5. In a railway vehicle, the combination with side frames having pedestals and binders therefor, of journal boxes having lateral projections forming taper guide ways to receive the pedestal legs and interposed spacing shoes, said guide ways being narrowest and in engagement with the shoes at the bottoms of the boxes.
6. A railway vehicle, comprising wheel

axles, side frames and journal boxes embodying unyielding frame-restraining means acting materially below the axle centers, 30 said side frames being otherwise free to move laterally within considerable limits.

7. A railway vehicle comprising wheel axles, a frame structure and journal boxes embodying unyielding frame-restraining 35 projections that engage the same materially below the centers of the wheel axles, said frame structure being otherwise free to move laterally within considerable limits.

8. A railway vehicle comprising wheel axles, side frames and unyielding frame-restraining means located and acting materially below the axle centers to prevent sidewise movement, said frames being otherwise free from restraint against such movement, within considerable limits.

In testimony whereof, I have hereunto subscribed my name this 18th day of June, 1910.

JOHN E. WEBSTER.
